ROOFING CONSTRUCTION

John G. Percy, Jr., Buffalo, N. Y.

Application April 19, 1937, Serial No. 137,605

10 Claims. (Cl. 108—13)

This invention relates to roof constructions.

One of the objects of this invention is to provide a roof which is of light weight and which may be quickly and easily applied to a building without requiring expert workmen and which will also be of low cost and attractive appearance. Another object of this invention is to provide a roof construction in which thin sheets of metal or other material may be used without necessitating the prefabricating of such sheets. It is also an object of this invention in which the imperviousness of metal covering sheets is combined with a heat insulating core or supporting member, to produce a roof of exceptional resistance to heat transfer. A further object of the invention is to provide a roof construction in which suitable supporting or core members may be used in conjunction with the thin impervious sheets and which roof construction is so formed that these core members may be made of composition boards of high heat insulating value. Another object is to provide a roofing which is so constructed that it forms its own flashing and counterflashing.

It is also an object of this invention to provide a construction whereby the sheets of metal or other roofing material may be held in place by the core members without the use of metal fastening devices or nails passing through or in contact with the metal covering. Still another object of the invention is to provide a roof construction in which a joint or seam is provided between adjacent sheets of covering material. Another object is to provide a roof of this kind with reinforcing members, if such are required. It is also an object of the invention to provide a roof which may be placed directly upon the rafters of a building without requiring the usual sheathing or roof boards, thereby reducing the cost and also the weight of the roof.

Other objects of the invention will appear from the following description and claims.

In the accompanying drawings:

Fig. 1 is a fragmentary perspective view of a roof partly broken away to illustrate the construction embodying this invention.

Figs. 2 and 3 are fragmentary perspective views of portions of the roof on an enlarged scale.

Fig. 4 is a fragmentary perspective view of a roof embodying this invention and showing an expansion joint for the flexible sheets.

Fig. 5 is a fragmentary edge view on an enlarged scale of the connection between covering sheets at the ridge of the roof.

Fig. 6 is a fragmentary section on a larger

scale, showing the manner of applying my improved roofing.

Figs. 7 and 8 are fragmentary sectional perspective views, on a still larger scale, showing steps of the process of applying my improved roof.

Figs. 9 and 10 are fragmentary sectional views, showing two additional steps in the applying of my improved roof.

Fig. 11 is a fragmentary section of a finished roof.

Fig. 12 is a perspective view of an implement which may be used in connection with the application of the sheet material to a roof.

Briefly stated my improved roof includes a plurality of core members which preferably are in the form of boards, panels or strips extending lengthwise of the roof and arranged in overlapping arrangement so that the lower edge of one core member or panel overlaps the upper edge of the next lower core member. The exposed surfaces and edges of these core panels are covered by suitable flexible sheet material which is impervious to moisture and substantially unaffected by weather. Preferably these sheets are made of any suitable metal which is sufficiently durable to withstand moisture and weather conditions. For example, thin sheet copper may be advantageously used for this purpose, since it will withstand exposure to weather for almost indefinite periods of time, and for the reason that it will acquire a film of oxide on its exposed surface which provides an attractive appearance. It will be understood, however, that it is not intended to limit this invention to the use of sheet copper since obviously there are other metals which can advantageously be used in the place of copper, and if desired, flexible non-metallic materials in sheet form may be used.

Referring to Figs. 6 to 10, inclusive, A, A', A², A³, and A⁴ represent core members or panels which are arranged in overlapping relation to each other so that the lower portions of all of the core members except the lowest overlap the upper edge portions of the next lower panels or core members respectively. These core members or panels may be wooden boards or they may be made of any of the well known heat insulating building materials which may, for example, be formed of vegetable fibers, pulp, or the like.

B', B², B³ and B⁴ represent successive sheets of flexible covering material which are applied respectively to the core members A, A', A², A³ and A⁴. Each of the flexible sheets has the lower edge portion thereof suitably arranged under the lower face of its core member and then extends

upwardly across the lower edge of the core member and then along the upper face of its core member and terminates at its upper edge between the overlapping parts of its core member and 5 the next higher core member.

In the practical application of my improved roofing construction, I preferably first secure the lowest core member or panel A loosely in place on the roof supporting structure, which may include rafters 15, and a strip 16 arranged at the 10 eave portion of the roof, for example, by loosely nailing the core member to the eave strip 16. An edge of the cover sheet B is then inserted between the lower surface of the core member A 15 and the strip 16 and while this sheet of flexible material is hanging down from the strip 16, nails or other fastening devices 17 may be driven firmly in place so that the lower edge of the sheet B will be clamped between the core member A and the 20 strip 16. The sheet B is then folded across the lower edge of the panel or core member A and across the upper face thereof and will terminate short of the upper edge of the core member A. The core member A may, consequently, also be 25 nailed adjacent to its upper edge, for example, by means of nails 18 arranged beyond the upper edge of the covering sheet B. The second covering sheet B' is then laid with an edge thereof in contact with the upper edge of the sheet B 30 and is temporarily held in place in this relation while lying over the lower sheet B and the next core member A' is secured in place to clamp the contacting edges of the cover sheets B and B' between the overlapping portions of the core 35 members A and A'.

Any suitable means for temporarily holding the sheet B' in place may be employed, and I have found that this can be very effectively accomplished by forming a fold or seam connecting the 40 upper edge of a lower sheet with the lower edge of the next higher sheet. Since the covering sheets are made of flexible material, such for example as thin sheet metal, the upper edge of a sheet can readily be turned over after the sheet 45 has been placed upon its core member, and in the construction illustrated by way of example, the upper edge of each covering sheet is provided with a turned over portion 20 under which the lower edge of the next higher sheet is placed.

50 By clinching the turned over part 20 at intervals, for example, by blows from a hammer, the part 20 will grip the lower edge of another sheet so as to frictionally hold such other sheet in place while the core member for the same is secured 55 in place. The turned over part 20 or other seam connecting adjacent sheets is very desirable, in that it forms a seal which effectively excludes air from passing through the spaces between adjacent sheets of covering material. Any other 60 seam or connection between sheets may be used, or if desired, the seam or connection may be omitted.

Upon placing the core member A' in overlapping relation to the upper edge of the core member A and over the adjacent edges of the sheets B and B', which may for example be effected by 65 means of nails 21 and 22, the sheet B' is folded over the lower edge of the core member A' and over the upper surface thereof. The securing in 70 place of the next sheet B², which is shown in Fig. 6 as temporarily clamped in place by the core member A², is then effected in the same manner as described for the sheet B' and these operations are repeated until the upper part or ridge 75 of the roof is reached. If nails 21 are used, they

are preferably driven home firmly so that the heads will be sunk into the core members and will be out of contact with the covering sheets, if the same are of metal. It is, however, possible to eliminate the nails 21 entirely, since the nails 5 18 and 22 at the upper portions of the panels beyond the covering sheets are ordinarily sufficient to secure the panels in place and to clamp the covering sheets between overlapping parts of the panels. 10

If the covering sheets of the roof are made of metal or other material which, if bent over, will stay in bent position, the flashing of the roof at the ridge may be readily formed as shown in Fig. 5, by bending, rolling, or folding the upper edges 15 of the upper sheets 25 and 26 of the roof upon each other to form a seam 27. These two up-standing edges may be pressed or clinched together, if the sheets 25 and 26 are of metal, and will form a tight seam at the ridge which eliminates the need for any special ridge member of the roof. If the covering sheets are made of a non-metallic substance, a similar construction may be employed and the upwardly extending member 24 may be cemented into the U-shaped 25 part 27. It will be understood, however, that it is not intended to limit this invention to the particular manner of forming of the flashing at the ridge of the roof, since any other form of ridge construction may be employed, if desired. 30

It is very desirable in roof construction to avoid having any of the nails or fastenings pass through a metal sheet of the roof, and in my improved roof, it will be noted that the securing of the cover sheets is effected without having any 35 nails or the like passing through or contacting with any covering sheets. This makes it possible to employ ordinary steel nails with a copper roof without danger of electrolysis, particularly since the holding of the panels and sheets in 40 place is mainly effected by these nails which are driven into the core panels above the upper edges of their covering sheets. If, however, it is found desirable to further secure the panels in place by nails 17 and 21, nails of the same metal as 45 covering sheets may be employed, for example, copper nails when copper roofing sheets are used, or the heads of the nails may be countersunk into the core panels as shown in the drawings. 50

I preferably provide means for positively holding the cover sheets against moving downwardly out of their operative positions. For example, I may provide interfitting depressions or recesses in the core panels and cover sheets, preferably in the overlapped portions of the sheets and panels, 55 so that the upper ends of the sheets will be firmly secured in place with reference to their core members. By providing such recesses or depressions in the overlapping portions of the core members, the weight of an upper core member, 60 or the nails or other securing devices will hold the upper member in clamping engagement to the lower member and will, consequently, prevent the indentations or depressions in the cover sheets from moving upwardly out of the recesses 65 formed in their core members. Such recesses may obviously be formed in any suitable or desired manner and if the core members are made of a relatively yielding material, such for example as any of the well known fiber boards, a 70 series of blows with a hammer or other rounded or blunt tool upon the overlapped portions of the roofing material may be sufficient to produce the necessary indentations in both the covering sheets and the core members. Preferably, 75

however, I provide the portions of the core members which are to be overlapped with longitudinally extending shallow grooves or recesses 30, which can be readily cut or formed in these members. A corresponding downwardly extending groove 31 is then formed in the cover sheets in such a manner as to extend into the grooves 30. These recesses may, of course, be formed in any suitable or desired manner either before or after laying the sheets on their core members. I prefer, however, to make the cover sheets of plain sheet metal which is quite thin so that the same can readily be formed into the desired shape. Consequently, such metal may be supplied to the roofers in long lengths of a definite width, and these lengths may be supplied in the form of rolls and sheets of the desired lengths and may, consequently, be readily cut from the long sheets. The portion of the flat metal sheets 20 which extend over the grooves 30 in the core members can, consequently, easily be pressed into the grooves to form the depressed portions 31 of the covering sheets.

If desired, this operation of forming the depressions in the cover sheets may be facilitated by the use of a forming implement as shown in Fig. 12, which may consist of a plate-like member 33 having a handle portion 34. The lower face of the plate-like member 33 may be provided with a longitudinally extending projection 35 which may be of a contour corresponding to that of the grooves 30 in the core members. Consequently, by positioning this plate member over the grooved portions of the core members and pressing downwardly on the same, the flexible covering sheets will be formed with depressions 31 as shown in the drawings. The forming implement may be moved lengthwise of the sheets so that the grooves 31 can be very quickly formed 40 in the covering sheets. This implement may also be used in connection with the turning over of the upper edges of the covering sheets, and for this purpose, the plate-like member 33 is also provided with an upwardly extending slot 36, parallel to the projection 35 and of such depth as to receive the upper edge of a covering sheet. In the use of this implement, in connection with readily flexible sheets such as thin copper, the forming implement may first be passed lengthwise of a covering sheet with the projection 35 arranged over the groove 30 of a core member to partially form the depressed portion 31 in the covering sheet. The implement may then be moved lengthwise over the covering sheet for a second time to completely form the depressed portion 31 in the covering sheet and during this second passage of the implement across the covering sheet, a corner of the sheet may initially be bent upwardly and passed into the slot 36 of this covering member. Upon moving the forming member lengthwise of the covering sheet, the entire upper edge of the sheet will be turned over in the groove 36 into the position shown in Fig. 8. Consequently, the upper edge of a covering sheet will be bent upwardly uniformly lengthwise of the sheet and at a definite distance with relation to the groove 30 in the covering member and this upwardly extending end portion, consequently, facilitates greatly the positioning of the succeeding sheet of covering material. This bent-over edge can then be easily completely bent over the next succeeding sheet, as shown in Fig. 9.

It will be readily seen that the depressed portions 31 and the grooves 30 very effectively hold

the covering sheets in place for the reason that the depression 31 of the covering sheet is arranged between overlapping portions of the core members so that either the nails or other fastening devices or the weight of the overlapping portions of the core members hold the depressions 31 in their grooves 30. In the case of snow, ice or wind loads on the roof, such loads or forces serve to increase the pressure tending to hold the depressions 31 in the grooves 30. The grooves 31, 10 in addition to holding the cover sheets in place, also serve to prevent water from passing upwardly by capillary action between the overlapping parts of adjacent sheets.

If the covering sheets of the roof are made of metal, it may be desirable to provide for the expansion and contraction of the metal covering sheets due to changes in temperature to which they are exposed. My construction lends itself readily to the provision of expansion joints 15 for the reason that in my improved roof, the covering sheets are frictionally held in place and not secured by means of nails or the like. Consequently, if the lengths of the covering sheets and the coefficient of expansion of the material of which they are made are sufficient to make the use of expansion joints desirable, the covering sheets may be formed in two or more parts or lengths rather than in a continuous length or sheet. In such a case, it is only necessary to 20 overlap adjacent ends of the parts of the sheets and the application of the roofing may then be proceeded with in the same manner as if a continuous sheet were employed. Since it is desirable in my improved roof to use thin sheets of 25 covering material, the double thickness of the metal at the overlapping portions is not sufficient to cause any difficulty and the roofer, consequently, proceeds with the folding over of the sheets and with the bending over of their upper 30 edges and the forming of the grooves 31 therein, if such are used, in the same manner as if a single length sheet were used. In Figs. 1 and 4, 40 represents the edges of overlapping parts of covering sheets, and in Fig. 4, 41 shown in broken 45 lines, represents the overlapped edge of the other part of the sheet. If desired, the overlapping end of a part or length of a sheet may be provided in the portion thereof covering the lower edge of a core member with drain holes or openings 42, 50 Fig. 4, through which any water which has passed between the overlapping portions of parts 55 of a sheet may drain. With my improved roof construction, no securing together of the overlapping edges is necessary, since these overlapping portions of the sheets will be held securely in place by the turned over edges 20 or other seams which may be employed and by the clamping or gripping of the sheets by the overlapping portions of the core members. The 60 seams formed by the over-turned edge 20 at the overlapping portions readily permit lengthwise movement of one part of the sheet relatively to another part at the joint.

My improved roof construction is also very 65 readily adaptable to roofs provided with hips, such for example as shown at C in Figs. 1 and 2, or valleys as indicated at D, Figs. 1 and 3, in which case the flashing and counterflashing can be formed by means of the roofing sheets themselves without requiring the usual additional parts. This will be readily apparent from Figs. 1 to 3 inclusive. In Fig. 3 is shown the manner in which the roofing is applied to valleys. The sheets at the portions of the roof which meet 70

to form a valley are left of sufficient length to extend beyond the valley and to be bent at the valley and extend in overlapping relation for short distances at each side of a valley. Because of the angular relationship between two abutting core panels at a valley, the covering sheet of each panel after being bent at the valley, will extend upwardly along the abutting panel at an angle. The upper edges of these bent portions of the sheets are then cut so as to lie substantially coincident with the upper edge portions of the sheets which they overlap. The end of one of the sheets is arranged underneath the other sheet at the other side of the valley, and its lower edge will incline upwardly as indicated at 45. The end portion of the other sheet extends over the outer surface of the latter sheet and its lower edge is indicated at 46 in Figs. 1 and 3. The upper edges of the overlapping portions of the sheets are secured to each other by the turned over seam 20. By means of this construction a flashing is formed which eliminates the use of the usual valleys and provides at the intersection of the two roof planes a portion of double thickness.

In the application of my improved roofing to a hip as clearly shown in Figs. 1 and 2, the sheets of covering material which meet at the hip are extended beyond the same, one being underneath the other in a somewhat similar manner as described in connection with the valleys, except that at the hips, the end portions of sheets when bent around the hip extend downwardly. The extreme overlapping ends of the sheets may, consequently, be bent under the lower edges of the core panels, and the edge 48 of one sheet, will lie underneath the other sheet, whose top edge may be cut as indicated at 49 to form an exposed end of the sheet. Since the hips and valleys are formed of double thickness of metal, these parts of the roof will be very durable and will amply protect the building against leaks.

At the ends of the roof, the covering sheets may be bent or folded over the ends of the core members in any suitable or desired manner. If the covering sheets are made of thin metal, the sheets are so applied to the core members as to extend to the desired distance beyond the outer edges of the same and the thin metal sheets can then be readily folded over the outer edges of the core members, as shown at 55, and secured on the underface of the same in any suitable manner. These folded ends 55 thoroughly cover the core members and the entrance of moisture into the space between the core members and the roofing sheets is avoided.

One of the advantages of my improved roofing construction is that the same lends itself particularly well to the use of heat insulating materials in the core. When a building is being re-roofed, the structure described may be placed on the former roof, and the core members, therefore, need not have the strength usually required in roof construction. If, however, it is desired to use my improved roof construction on new roofs and to omit the usual sheathing or roof boards, and at the same time to employ core members of heat insulating material and of little strength, a series of reinforcing bars 70 may be employed extending crosswise of the rafters. I have found that these reinforcing bars can advantageously be inserted between the overlapping portions of adjacent core members. In Figs. 6, 10 and 11, I have shown reinforcing bars 57 which may, for example, be set in op-

positely disposed grooves or recesses 58 and 59 formed in the overlapping portions of the lower and upper core members. These bars may, for example, be square in cross section, although bars of any other cross-sectional shape may be employed, if desired. When square bars are used, V-shaped notches or recesses are formed in the core members and, if desired, these recesses may be cut or formed simultaneously with the recesses 30 and at definite distances therefrom. The reinforcing bars may be inserted into the recesses and secured to the rafters by means of staples 60 or the like, and when these staples are used, the nails 18 and 22 may be omitted. It is also possible, if desired, to omit the nails 21, 15 since the staples and reinforcing bars will secure the panels to the rafters in such a manner that the portions of the panels which overlap the next lower panels will be securely clamped over the next lower panels. 20

The reinforcing members described have the further advantage that when an overlapping core member is positioned over the reinforcing bar, the groove 59 therein is placed into registration with the bar 57 so that successive core members will be correctly positioned with relation to each other. It will be noted that these reinforcing bars are also out of contact with the sheets of roofing material. Other types of reinforcing members may, of course, be provided if 30 desired.

In order to illustrate the application of my roof to a building, I have shown in Fig. 6, two core members on which the sheets of covering material are applied. An edge of the third covering sheet B² has been secured in the bent-over portion 20 of the covering member B' and the next core member A² has been secured in place by means of a countersunk nail 21. The covering sheet B² is then bent over the lower edge and upper face of the core member A² and will lie across the groove 30, as shown in Fig. 7. A part of the sheet B² is next pressed into the groove 30 of the core member A² and finally the upper edge of the covering sheet B² is folded 45 upwardly, for example, by means of the slots 36 of the forming implement. The next sheet is then positioned in place and the turned over edge 20 is bent over against the edge of the next sheet B³, for example, by means of hammer blows 50 at intervals lengthwise of the turned over part 20. If the core members are made of a heat insulating material of insufficient strength to adequately support the roof and if reinforcing members are required, the reinforcing bar 57 is 55 then positioned in the groove 58 and fastened by means of staples 60.

The next cover sheet B⁴ is then applied to the bent-over part of the lower sheet, as has already been described, and the roofing is then proceeded 60 with as already described. As shown in Figs. 6 and 10, the core members A³ and A⁴ are somewhat separated in order to show clearly the fold or seam between adjacent sheets and the overlapping core members. Preferably the upper 65 core member, however, is pounded tightly into place at the overlapping part by means of a mallet as shown in Fig. 11, and if the core member is of heat insulating material, the upper part of the staple 60 will readily embed itself in the 70 material of the upper core member and the pounding down of the core member will also form a tight joint at the seam between the two covering members. If the core members are of wooden boards or of material of sufficient 75

strength to support roof loads, the reinforcing bars are, of course, omitted.

The roof construction described has the advantages that it is quick and inexpensive to apply to a building, since the flexible covering material may be used in the form of standard sheets of a width to cooperate with the width of the core members and may be thin enough so that no performing of these sheets is necessary. When thin sheet metal is used, the bending of the sheets by hand over the panels not only reduces the cost of laying the roofing but also greatly increases the beauty of the same since, for example, when bending a sheet over the lower edge of a panel, the metal at the bend may be more or less irregularly formed by hand, so that hand worked effect is produced and the rigid straight lines at the bend are avoided. The folded over upper edge of each covering sheet which forms with the next sheet a seam, forms also a substantially air-tight joint between adjacent roofing sheets. By means of the construction described, the thin sheets of covering material, particularly if they are made of metal, will form a roof covering which is substantially impervious not only to water, but also to air, so that the seepage of air through the roof is reduced to a minimum. If the core members are made of a heat insulating material, the roof will in addition to stopping the transfer of heat through the same by seepage of air, also stop the passage of heat through the roof by conduction, so that a roof of exceptional heat insulating properties is produced. The overlapping arrangement of the core members and the termination of each covering sheet below the upper edge of its core member prevents the passage of heat through the roof by conductivity through the covering sheets, since the air in the interior of the roof will not come in contact with the covering sheets in the overlapping portions of the core members.

While my improved construction has herein been described only as applied to a roof, it will be obvious that it may equally well be used in forming exterior or interior side walls, and consequently, the word "roof" is herein used to include any wall construction.

I claim as my invention:

1. A roof including a plurality of core members having flat faces and arranged with the lower edge of one core member overlapping the upper edge of a lower core member, a portion of the flat face of a lower core member which is overlapped by another core member having a longitudinally extending recess formed therein, a sheet of metal covering said recessed core member and having a part extending into said recess, a sheet of metal covering the next higher core member and extending over the lower edge thereof and under the part overlapping said lower core member and bridging said recess, and means for securing said core members in operative relation to each other to clamp said sheets between overlapping portions of said core members and to hold said part of said sheet of said lower core member in said recess.

2. A roof formed of a series of core members extending lengthwise of the roof in a substantially horizontal direction, a sheet of flexible covering material extending from the under surface of a core member over the lower edge thereof and upon the upper surface thereof, another core member arranged with its lower edge in overlapping relation to said first core mem-

ber, a sheet covering said second core member and held in contact with the first sheet between the overlapping portions of said core members, said sheets being divided lengthwise into separate parts arranged in overlapping relation to each other to permit each part of each sheet to expand and contract independently of the other part, the overlapping portion only of one part of a sheet being provided at the lower edge of its core member with holes for the escape of moisture which may enter between overlapping parts of a sheet.

3. A roof formed of a series of core members arranged in overlapping relation with the lower edge of one core member overlapping the upper edge of the lower core member, a metal sheet for each core member extending from the under surface thereof into the overlapping portion between adjacent core members and terminating at a distance from the upper edge of its core member, and reinforcing bars extending lengthwise of said cores and arranged in the overlapping portions thereof out of contact with said metal sheets.

4. A roof formed of a series of core members arranged in overlapping relation with the lower edge of one core member overlapping the upper edge of the lower core member, a metal sheet for each core member extending from the under surface thereof into the overlapping portion between adjacent core members and terminating at a distance from the upper edge of its core member, and reinforcing bars extending lengthwise of said cores and arranged in the overlapping portions thereof out of contact with said metal sheets, the overlapping portions of said core members being grooved to receive said reinforcing members and for positioning adjacent core members in correct relation to each other.

5. A roof construction including a plurality of longitudinally extending core members arranged one above the other and having the lower edge of one core member overlap the upper edge of a lower core member, some of said core members having end portions thereof terminating adjacent to the other core members extending at an angle thereto, a metal sheet for each core member extending around the lower edge portion thereof and over the exposed surface thereof and between the overlapping portions of said core members, the sheets covering core members arranged in angular relation to other core members having end portions overlapping said other core members to form weathertight angular portions on said roof.

6. A roof construction including a plurality of longitudinally extending core members arranged one above the other and having the lower edge of one core member overlap the upper edge of a lower core member, some of said core members having end portions thereof terminating adjacent to other core members extending at an angle thereto, a metal sheet for each core member extending around the lower edge portion thereof and over the exposed surface thereof and between the overlapping portions of said core members, a folded seam connecting adjacent sheets and arranged between said overlapping portions, a sheet covering one core member extending beyond the end thereof and arranged in overlapping relation to the sheet of an adjacent core member arranged at an angle to said first core member, said overlapping portion of said sheets having their upper edges bent over the lower edge of the next higher sheet.

7. A roof including a plurality of core panels of heat insulating material having substantially flat upper faces and arranged with the lower portion of one panel overlapping the upper portion of the next lower panel, a sheet of flexible metal covering for each panel, each sheet extending from the under face of its panel across the lower edge and upper face thereof and terminating between the overlapping portions of adjacent panels, the overlapped portions of said panels having grooves in the flat faces thereof into which said metal sheets enter to secure said sheets against displacement relatively to said panels.
8. A roof including a plurality of core panels of heat insulating material having substantially flat upper faces and arranged with the lower portion of one panel overlapping the upper portion of the next lower panel, a sheet of flexible metal covering for each panel, each sheet extending from one overlap across the lower edge and upper surface of a panel to another overlap, the opposite edges of said sheets terminating in the overlaps, whereby the cover sheets are substantially out of contact with air on the underside of the roof to reduce heat conductivity through the roof, the overlapped portions of said panels having grooves in the flat faces thereof into which said metal sheets enter to secure said sheets against displacement relatively to said panels.
9. A roofing member including a core panel arranged to be secured on a roof in overlapping relation to a similar core panel, said core panel having a recess formed in a flat surface thereof at a portion which is to be overlapped by a next higher panel, a metal sheet covering said core member and having a portion thereof bent to extend into said recess and adapted to be confined in said recess by the overlapping flat portion of the next higher core panel to hold the metal sheet in correct relation to its core panel.
10. A roof including rafters and a plurality of core members extending longitudinally of said roof and transversely of said rafters and having flat upper and lower faces and arranged with the lower edge of one core member overlapping the upper edge of a lower core member, the portion of the flat face of a lower core member which is overlapped by another core member having a depression formed therein, a metal sheet covering each core member, each metal sheet being arranged with its lower edge below the bottom surface of its core member and extending around the lower edge and over the top surface thereof, and terminating in said overlapped portion in contact with the lower portion of the next higher sheet, the metal sheets of said core members terminating below the upper edges thereof and having portions extending into said recesses in the depressions of said core members, and fastening means extending to the upper portion of each core member into said rafters and arranged above and out of contact with said sheets and being covered by the next higher core member.

JOHN G. PERCY, JR.
